UNITED STATES PATENT OFFICE.

CHARLES F. RUTTMAN, OF MOSCA, COLORADO.

WIRE STRETCHER.

Application filed May 24, 1923. Serial No. 641,106.

To all whom it may concern:

Be it known that CHARLES F. RUTTMAN, a citizen of the United States of America, residing at Mosca, in the county of Alamosa and State of Colorado, has invented new and useful Improvements in Wire Stretchers, of which the following is a specification.

The object of the invention is to provide a simple, strong and efficient fence building or wire stretching apparatus suitable for simultaneously stretching a plurality of wires or runners in the building of a fence; and with this object in view the invention consists in a construction and combination of parts of which a preferred embodiment is shown in the accompanying drawings, wherein:—

Figure 1 is a perspective view of the apparatus arranged in an operative position 20 with its frame seated against a fence post.

Figure 2 is a side elevational view.

Figure 3 is a plan view.

Figure 4 is a horizontal longitudinal sectional view.

The apparatus consists essentially of a supporting frame having top and bottom marginal bars 10 and 11 connected near their front ends by an upright bar 12 and near their rear ends by an upright bar 13, and 25 a follower frame mounted for sliding movement in the supporting frame and consisting of upper and lower ratchet bars 14 and 15 connected by a head 16 to which the runner wires 17 are adapted to be attached, said 30 head including a bar 18 terminally extended to fit in guides formed between parallel spaced elements of said top and bottom supporting frame bars 10 and 11. The head is 35 preferably provided with a clamp bar 19 secured by screws or bolts 20 as a means of 40 securing the wire runners or fabric thereto, it being understood that the apparatus may be used either for the stretching of separate runner wires or of a wire fabric of a width 45 necessary for the height of the fence.

Mounted upon the marginal supporting frame bars are operating levers 21 split to straddle the ratchet bars of the follower frame and provided with operating pawls 22 50 for engagement with the teeth of the ratchet bars to advance the follower frame in the direction necessary to stretch the fence wire, and mounted upon the rear upright 13 of the supporting frame are the holding pawls 23 55 also adapted for engagement with the teeth of said ratchet bars for locking the follower

frame in its adjusted positions or the position to which it is moved successively by the operation of the levers 21. Guide pins 24 span the interval between the spaced side 60 elements of the upright 13 to form rests for the ratchet bars which are preferably pivoted as at 25 to the head 16.

The forward ends of the marginal bars of the supporting frame are provided with 65 shoes 26 for engagement with a fence post 27 which is preferably the corner post of a fence structure.

In order to maintain the supporting frame in its proper position there is employed a 70 brace frame 27 extended laterally from and in a plane perpendicular to that of the supporting frame and consisting of an obliquely disposed rod 28 connected at its lower end with a horizontal rod 29 engaged with an 75 eye 30 designed for the reception of a stem or pin 31 to be driven into the ground. The upper end of the diagonal brace rod is provided with a depending slotted eye 32 and the corresponding end of the horizontal 80 brace rod is provided with an upstanding slotted eye 33 for respective engagement with the rear ends of the marginal bars 10 and 11 of the supporting frame.

Having described the invention, what is 85 claimed as new and useful is:—

1. A fence wire stretcher having a supporting frame provided with marginal bars terminating at their forward ends in shoes for engagement with a fence post, a follower 90 frame mounted to slide in the supporting frame and having a head provided with means for traversing said marginal bars, and with means for engaging fence wires, said follower frame also including rearwardly directed ratchet bars, holding pawls mounted upon the supporting frame for engagement with the teeth of the ratchet bars to maintain the follower frame in adjusted positions, operating levers mounted upon the supporting frame and provided with pawls for engagement with the teeth of the ratchet bars to move the follower frame longitudinally of the supporting frame, and a transversely disposed brace frame for 95 maintaining the upright position of the supporting frame.

2. A fence wire stretcher having a supporting frame provided with marginal bars terminating at their forward ends in shoes for engagement with a fence post, a follower 100 frame mounted to slide in the supporting 105 frame and having a head provided with means for traversing said marginal bars, and with means for engaging fence wires, said follower frame also including rearwardly directed ratchet bars, holding pawls mounted upon the supporting frame for engagement with the teeth of the ratchet bars to move the follower frame longitudinally of the supporting frame, and a transversely disposed brace frame for maintaining the upright position of the supporting frame.

- frame and having a head provided with means for traversing said marginal bars, and with means for engaging fence wires, said follower frame also including rearwardly directed ratchet bars, holding pawls mounted upon the supporting frame for engagement with the teeth of the ratchet bars to maintain the follower frame in adjusted positions, operating levers mounted upon the supporting frame and provided with pawls for engagement with the teeth of the ratchet bars to move the follower frame longitudinally of the supporting frame, and a transversely disposed brace frame for maintaining the upright position of the supporting frame, the said marginal bars of the supporting frame having spaced elements forming guides for the reception of the extremities of a head of the following frame.
- 16 3. A fence wire stretcher having a supporting frame provided with marginal bars terminating at their forward ends in shoes for engagement with a fence post, a follower frame mounted to slide in the supporting frame and having a head provided with

means for traversing said marginal bars, and with means for engaging fence wires, said follower frame also including rearwardly directed ratchet bars, holding pawls mounted upon the supporting frame for engagement with the teeth of the ratchet bars to maintain the follower frame in adjusted positions, operating levers mounted upon the supporting frame and provided with pawls for engagement with the teeth of the ratchet bars to move the follower frame longitudinally of the supporting frame, and a transversely disposed brace frame for maintaining the upright position of the supporting frame, and consisting of connected oblique and horizontal rods provided at their intersection with an eye for an anchor pin and at their other extremities with eyes for sliding engagement with the extremities of the marginal bars of the supporting frame.

In testimony whereof he affixes his signature.

CHARLES F. RUTTMAN.
